ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

AMMUNITION HOISTING AND LOADING APPARATUS FOR ORDNANCE.

1,402,400.

Specification of Letters Patent.

Patented Jan. 3, 1922.

Application filed September 4, 1920. Serial No. 408,322.

To all whom it may concern:

Be it known that we, Sir ARTHUR TREVOR DAWSON, Bart., and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to Ammunition Hoisting and Loading Apparatus for Ordnance, for which we have filed an application in Great Britain, No. 21,083, dated Aug. 27, 1919, and of which the following is a specification.

This invention relates to ammunition hoisting and loading apparatus for ordnance.

According to the invention any of the containers, cages or the like used in connection with the supplying of powder charges to the gun is provided with a rotary or rocking powder charge receptacle which is so constructed and arranged in relation to the opening or openings in the container or cage as to be itself capable of closing the said opening or openings in a flash-proof manner. In one arrangement the said receptacle may be used in conjunction with a container attached to the rotary trunk through which ammunition is carried by a lifting cage to the gun, this container projecting into the magazine and being formed with openings through which the powder charges enter and leave the receptacle. The latter moves in contact with curved surfaces in the container and the construction is such that in all its positions it prevents a flash in the trunk from passing through the container to the magazine; the construction of the said receptacle is also such that in all its positions (taken in conjunction with the lifting cage) the charge contained in the receptacle is flash-proof in relation to the inside of the trunk and in all its positions except that in which it receives the powder charges, the charge is flash-proof in relation to the magazine.

When the receptacle is used in conjunction with a lifting cage, it may be of the same general construction as that described with reference to the container and serves when moved into a suitable position to cut off communication between the trunk and the powder charges carried by the receptacle.

In order that the said invention may be clearly understood and readily carried into effect the same will be more fully described with reference to the accompanying drawings, in which:

Figure 1 is a sectional elevation of the aforesaid container and a lifting cage each provided with a powder charge receptacle constructed in accordance with this invention,

Figure 2 is a section taken approximately on the line 2, 2 of Figure 1, and

Figure 3 is a sectional elevation showing the container, the lifting cage and a gun loading cage, all provided with the said powder charge receptacles and also showing interlocking safety devices hereinafter referred to.

A is the rotary trunk, B is the container which is attached to the trunk A and projects into the magazine, B' is the powder charge receptacle of this container, C is the lifting cage, C' is the powder charge receptacle of this cage, D (Figure 3) is the gun loading cage and D' is the powder charge receptacle of this cage.

In the example shown the powder charge receptacle B' is of substantially U shape in cross-section and has trunnions b, b mounted in the end walls b', b' of the container B, so as to enable the receptacle to swing about a longitudinal axis. The said receptacle is provided with longitudinal webs B², B² having curved surfaces and the outer ends of the limbs B³, B³ also have curved surfaces, these various curved surfaces moving in contact with the cylindrical inner surface of the container. The latter is formed with a receiving opening B⁴ through which the powder charges are inserted into the receptacle B' when the latter occupies the receiving position with its center-line 1 at 1^a and is also formed at a lower level than, and substantially opposite, the receiving opening with a discharging opening B⁵ through which the powder charges roll from the receptacle when the latter is displaced into the discharging position with its centre line 1 at 1^b.

The receptacle is displaced into its various positions by a handle B^x. It will be observed that a receptacle constructed in the manner above described provides an arrangement for transferring the powder charges

from the magazine to the lifting cage in such a manner that the receptacle in all its positions, renders it impossible for a flash in the trunk to enter the magazine past the receptacle. Moreover in the receiving position of the receptacle and in the intermediate or waiting position shown by full lines in Figure 1, the powder charges therein are flash-proof in relation to the inside of the trunk; 10 a similar effect is obtained when the receptacle is in the discharging position because at such times the lifting cage C is in its lowermost position closing the discharging opening B⁵ of the container.

15 The receptacle C' of the lifting cage C and the receptacle D' of the gun loading cage D (Figure 3) are constructed in a similar manner to the receptacle B' above described except that the receptacle C' has 20 only one web C²; the receptacle C' prevents a flash in the trunk from reaching the receiving opening C⁴ past the said receptacle when the latter occupies the receiving and discharging positions in which the centre 25 line 3 is at 3^a and 3^b respectively (see Figure 1) and also ensures that the powder charges in the receptacle shall be flash-proof in relation to the trunk when this receptacle occupies the position shown by full 30 lines in Figure 1.

The rotary receptacle D' of the gun loading cage D serves to completely close the opening in the cage through which the charges enter except when the charges are 35 being received from the lifting cage C.

The receptacle D' is arranged above the projectile container or compartment of the cage as is described in the specification of our copending application, Serial No. 40 408,326, filed September 4, 1920.

Means are provided whereby the receptacle B' of the container B is prevented from being placed in the discharging position until the lifting cage receptacle C' is 45 in the receiving position these means including a plate B⁶ (Figure 3) keyed to the trunnion pin of the receptacle B', a bell crank lever B⁷ (pivoted on the trunk structure) to which a locking bolt B⁸ is attached and a 50 spring B⁹ which normally keeps the bolt B⁸ in the way of the plate B⁶ (as shown by chain lines) when the receptacle B' is in its receiving position. When the cage C descends a tappet lever C⁵ keyed to the trunnion pin of the cage receptacle C' is moved 55 as a result of the rotation of the receptacle C' and operates the bell crank lever B⁷ to withdraw the bolt B⁸ and the receptacle B' can then be moved to the discharging position.

Means are provided for automatically moving the receptacle C' of the lifting cage to the receiving position, these means including a pinion C⁶ (Figure 3) (keyed to 65 the trunnion pin of the receptacle C') which

meshes with a sector C⁷ pivoted on the cage frame and provided with a roller C⁹. A centering spring C⁸ is provided to replace and retain the receptacle C' in its normal position. A hinged cam A' pivoted on the trunk structure and locked automatically by a hand operated bolt A² is provided. When the cage C descends the roller C⁹ engages with this cam to move sector C⁷ and thereby place the receptacle C' in the receiving position. The retaining bolt A² is then withdrawn thus allowing the receptacle C' to move to its normal position under the action of the spring C⁸. The tappet lever C⁵ disengages the bell crank lever B⁷ and this 70 allows the bolt B⁸ to lock the plate B⁶ when the receptacle B' is turned to receive further charges. The cam A', displaced by the spring C⁸, when the receptacle C' is in its normal position, automatically returns 75 to its operative position under the action of a spring A³ and is locked by the bolt A² when the cage C ascends.

When the cage C ascends to discharge into the gun loading cage D a cam A⁴ pivoted on the trunk and placed in its operative position on the descent of the gun loading cage by means of a bell crank A⁹, operates the roller C⁹ and places the receptacle C' in its discharging position.

If the lifting cage C arrives in its top position before the gun loading cage D is down, the receptacle C' remains in its normal position until the gun loading cage descends. When the cam A⁴ is then moved 90 through the action of a stop E on the cage D and the bell crank lever A⁹, it engages the roller C⁹ and places the receptacle C' to its discharging position. Similar means are employed to retain the receptacle D' of the 95 gun loading cage D in its normal position if the lifting cage C is not in the top position and to place the receptacle D' in the receiving position when the lifting cage reaches its top position. A cam A⁵ is pivoted to the trunk and is moved to its operative position by the lifting cage C coming against a bell crank lever A⁶. This cam when displaced to operative position engages a roller D² on a sector D³ on the gun 100 loading cage D, thereby rotating a pinion D⁴ keyed on the trunnion of the gun loading cage receptacle D'. Springs A⁷ and A⁸ are provided for normally holding the cams A⁴ and A⁵ in their inoperative positions. 105 When the gun loading cage D is charged, if the lifting cage C is lowered or the gun loading cage D is raised, the receptacles of both cages are moved automatically by the springs C⁸ and A¹⁰ respectively.

Assume the gun loading cage D is raised, the roller D² moves up the face of the relatively stationary cam A⁵ (operated on by the spring A¹⁰) until its receptacle is stopped in the normal position. The action 110

of raising the gun loading cage allows the cam A^4 to move to its inoperative position under the influence of the spring A^7 and the bell crank A^9 . The lifting cage receptacle 5 C' is then free to move to its normal position under the action of the spring C^8 . If the lifting cage C is lowered before the gun loading cage D is raised, the actions of the cam A^5 and the lever A^6 are similar to 10 those above described.

What we claim and desire to secure by Letters Patent of the United States is:—

1. In ammunition supply apparatus for ordnance, the combination with a powder 15 charge container having an opening for the entry of powder charges and also having an inner cylindrical surface, and a powder charge receptacle movable within said container, with parts of said receptacle in contact with said inner cylindrical surface whereby said receptacle, in moving from the position in which it receives the powder charges through said opening, itself closes this opening in a flash-proof manner.

2. In ammunition supply apparatus for ordnance, the combination with a powder charge container having an opening for the entry of powder charges and also having an inner cylindrical surface, and a powder 30 charge receptacle movable within said container about a longitudinal axis, with parts of said receptacle in contact with said inner cylindrical surface whereby said receptacle, in moving about said axis from the position 35 in which it receives the powder charges through said opening, itself closes this opening in a flash-proof manner.

3. In ammunition supply apparatus for ordnance, the combination with a powder 40 charge container having a lateral opening for the entry of powder charges and also having an inner cylindrical surface, and a powder charge receptacle movable within said container about a longitudinal axis, 45 with parts of said receptacle in contact with said inner cylindrical surface whereby said receptacle, in moving about said axis from the position in which it receives the powder charges through said opening, itself closes 50 this opening in a flash-proof manner.

4. In ammunition supply apparatus for ordnance, the combination with a powder charge container having a lateral opening for the entry of powder charges, of a powder 55 charge receptacle which has limbs giving it a U-shaped cross section and which is mounted in said container to turn about a longitudinal axis, the limbs of said receptacle moving in contact with the inner cylindrical 60 surface of said container.

5. In ammunition hoisting apparatus for ordnance, the combination with the ammunition trunk and the lifting cage to which powder charges pass through an opening in 65 said trunk, of a powder charge container

having a lateral receiving opening and a lateral discharging opening and also having an inner cylindrical surface, means for attaching said container to the trunk with the discharging opening of the container opposite the opening in the trunk and a powder charge receptacle which has limbs giving it a U-shaped cross section and which is mounted in said container to turn about a longitudinal axis, the limbs of said receptacle moving in contact with the inner cylindrical surface of said container.

6. In ammunition hoisting apparatus for ordnance, the combination with a powder charge lifting cage having a lateral opening 80 for the entry of powder charges and also having an inner cylindrical surface, of a powder charge receptacle which has limbs giving it a U-shaped cross section and which is mounted in said cage to turn about a longitudinal axis, the limbs of said receptacle 85 moving in contact with the inner cylindrical surface of said cage.

7. In ammunition hoisting apparatus for ordnance, the combination with a powder 90 charge lifting cage having a lateral opening for the entry of powder charges and a lateral opening for the discharge of the powder charges and also having an inner cylindrical surface, of a powder charge receptacle which 95 has limbs giving it a U-shaped cross section which is mounted in said cage to turn about a longitudinal axis, the limbs of said receptacle moving in contact with the inner cylindrical surface of said cage.

8. In ammunition hoisting apparatus for ordnance, the combination with a gun loading cage for lifting shells and powder charges to the gun, said cage having a lateral opening for the entry of the powder charges 105 and also having an inner cylindrical surface, of a powder charge receptacle which has limbs giving it a U-shaped cross section which is mounted in said cage to turn about a longitudinal axis, the limbs of said receptacle moving in contact with the inner cylindrical surface of said cage.

9. In ammunition hoisting apparatus for ordnance the combination of the elements claimed in claim 5, with a safety device for 115 preventing the receptacle of the container from being moved to its discharging position unless the receptacle of the lifting cage is in the correct receiving position.

10. In ammunition hoisting apparatus for ordnance the combination of the elements claimed in claim 6, with a safety device for preventing the receptacle of the container from being moved to its discharging position unless the receptacle of the lifting cage 125 is in the correct receiving position.

11. In ammunition hoisting apparatus for ordnance, the combination of the elements claimed in claim 5, with a safety device for preventing the receptacles of the container 130

from being moved to its discharging position unless the receptacle of the lifting cage is in the correct receiving position, and a safety device for preventing the latter receptacle from being moved to its discharging position unless the receptacle of the gun loading cage is in the correct receiving position.

12. In ammunition hoisting apparatus for ordnance, the combination of the elements claimed in claim 6, with a safety device for preventing the receptacle of the container from being moved to its discharging position unless the receptacle of the lifting cage is in the correct receiving position, and a safety device for preventing the latter receptacle from being moved to its discharging position

tion unless the receptacle of the gun loading cage is in the correct receiving position.

13. In ammunition hoisting apparatus for ordnance, the combination of the elements claimed in claim 8 with a safety device for preventing the receptacle of the container from being moved to its discharging position unless the receptacle of the lifting cage is in the correct receiving position, and a safety device for preventing the latter receptacle from being moved to its discharging position unless the receptacle of the gun loading cage is in the correct receiving position. 30

In testimony whereof we affix our signatures.

ARTHUR TREVOR DAWSON.
JAMES HORNE.
